UNITED STATES PATENT OFFICE

LEONARD M. MONDRAY, OF CHICAGO, ILLINOIS, ASSIGNOR, BY MESNE ASSIGNMENTS, TO THE CARDEL COMPANY, INC., OF CHESTER, PENNSYLVANIA, A CORPORATION OF DELAWARE

TEMPORARY GOVERNOR

Application filed January 21, 1929. Serial No. 333,813.

This invention relates to a temporary governor for application to a carburetor of an automotive vehicle which governor may be readily applied to the carburetor for preventing operation of the vehicle above a certain speed when a new vehicle is driven from the factory to some distant point.

An object of the invention is to provide a temporary governor for application to automobile carburetors which is light, compact, readily applied and removed, and which may be sealed in position against surreptitious removal or tampering.

Another object of the invention is to provide a temporary governor for application to automobile carburetors for limiting the speed of the vehicle and which governor is sealed against surreptitious removal and is provided with means for preventing tampering with the governor while in sealed position on the carburetor for increasing the speed of the vehicle beyond that determined by the governor.

A further object of the invention is to provide a temporary governor for application to automobile carburetors which is compact, light, readily applied and removed, economical to manufacture and efficient in service, and one which may be readily and conveniently carried when not in use.

The above, other and further objects of the invention will be apparent from the following description, accompanying drawings and appended claims.

One form of the invention is illustrated in the accompanying drawings and the views thereof are as follows:

Figure 1 is a top plan view of a carburetor having attached thereto a temporary governor embodying this invention.

Figure 2 is a side elevational view of the carburetor and governor of Figure 1.

The governor of this invention is of course applicable to every make of carburetor, the shape of the governor being made to correspond to the different makes of carburetors so that the same may be effectively sealed against excessive speed.

The carburetor chosen to illustrate the selected form of the invention is of standard

make and includes a throat 1 terminating in a flange 2 which is connected to the intake manifold of the automobile engine. A shaft 3 extends transversely through the throat 1 and carries the usual butterfly valve in the 55 throat.

A lever 4 has a hub 5 which is secured to the shaft 3. The lever 4 is arranged with oppositely extending ends 6 and 7, the end 7 arranged to be connected to a suitable throttle control. The end 6 extends beyond the shaft 3 for contacting a pin 8 disposed below the shaft 3 for limiting the maximum opening of the butterfly valve.

The illustrated form of the temporary governor includes a casting 9 having a curved portion 10 for fitting against the throat 1. The portion 10 has hooks 11 provided at its rear end for engaging over the pin 8 to aid in supporting the casting 9 in position. The upper surface of the casting 9 is inclined downwardly and forwardly from the hooks 11. The casting is provided with side members 13 which straddle the carburetor and rest on the flange 14 of the same. Lateral ears 15 are formed with the casting which ears are apertured to receive the ends of a U-bolt 16 which passes underneath the carburetor and extends upwardly through the apertures in the ears 15. 80

Nuts 17 are applied over the upper threaded ends of the U-bolt when the same is inserted through the ears for fastening the casting 9 to the U-bolt thereby attaching the temporary governor securely in position on 85 the carburetor.

The upper inclined surface 12 of the casting 9 is provided with a dovetail recess 18 in which is inserted a hardened steel plate 19 for underlying the end 6 of the throttle arm 4. This plate is provided at this point to prevent an operator of a vehicle to which the governor is attached from filing the casting to enable greater speed of the vehicle. The hardened steel plate prevents ready filing and also it indicates marks of tampering.

The upper ends of the U-bolt 16 are provided with holes 20 passing through the same for the reception of a sealing wire 21 which is passed through these holes after the nuts 100

17 have been tightened and the ends of the wire 21 are brought together and sealed by a lead or similar seal 22.

5 A temporary governor embodying this invention is readily applied to a carburetor of an automobile when it is desirous of driving the automobile from the factory to some distant point so that the operator of the vehicle will not drive the same at excessive speed 10 and thereby damage if not ruin the automobile. The governor is applied as shown and described and sealed and arranged with a hardened steel plate 19 underlying the end 6 of the throttle lever 4. An automobile delivered at its destination with the seal intact and with the hardened steel plate also intact indicates immediately that the automobile has not been driven at speed in excess of that determined by the size and arrangement of 15 20 the temporary governor casting 9. Should however an automobile be delivered with the seal broken or with the steel plate 19 damaged, then such state of affairs would indicate immediately that tampering had occurred to the vehicle en route enabling the recipient of the automobile to immediately investigate and determine what if any damage has been done to the same.

30 Should it so happen that a great number of new automobiles are to be driven away from a factory, then the person in charge of the drive away would be supplied with a great number of these temporary governors and fasten and seal the same to the carburetors of all of the automobiles in the drive away thus assuring operation of the automobiles at a conservative speed which would not damage the same in transit.

40 It is understood of course that the castings 9 and the other parts comprising the temporary governor of this invention may be arranged and shaped to conform to the shape and arrangement of any standard carburetor in use and invention therefore is not to be 45 limited to the exact form, arrangement and disposition of the parts as illustrated in the drawings.

50 The throttle lever 4 is provided with spaced lugs 23 and 24 through which passes 55 an adjusting screw 25 which is threaded into the lugs and in cooperation with the pin 8 determines the extent of movement of the butterfly valve in counterclockwise direction as observed in Figure 2.

55 The invention has been described herein more or less precisely, yet it is to be understood that changes may be made in the arrangement and proportion of parts and that equivalents may be substituted without departing from the spirit and scope of this invention.

60 The invention is claimed as follows:

1. A temporary governor for application to an automobile carburetor including a member temporarily applied adjacent the throt-

tle lever to limit movement of the same in the opening direction, a clamp surrounding said carburetor for securing said member to the carburetor in operative position, means for locking and sealing said member and said clamp together, and other means for indicating tampering with said governor. 70

2. A temporary governor for application to an automobile carburetor including a member positioned on the carburetor underlying the throttle lever to limit movement of the same in its opening direction, a U-bolt about the carburetor and cooperating with said member to secure the same in position on the carburetor, nuts on the ends of said bolt, and a wire passing through the ends of said bolt above the nut and having its end sealed against unauthorized removal. 75 80

3. A temporary governor for application to an automobile carburetor comprising a member applied to the carburetor and underlying the throttle lever of the same, means for securing said member in immovable position on the carburetor, means for locking and sealing said member and said first mentioned 90 means against unauthorized removal, and said member being provided with a hardened steel plate underlying the throttle lever and arranged to be contacted by the same when said lever is moved to the maximum opened 95 position as determined by said member.

4. A temporary governor for automobile carburetors including in combination a stop member applied to said carburetor underlying the throttle lever to limit the movement 100 of the same in opening direction, said stop member having a hardened steel inset for contact by the throttle lever, means for securing said stop member in position, and means for sealing said member and said securing means against unauthorized removal. 105

5. A temporary governor for automobile carburetors including in combination a stop member applied to said carburetor underlying the throttle lever to limit the movement 110 of the same in opening direction, said member having spaced rearwardly extending portions for engaging the throttle throat of the carburetor and having a hook for engaging a projection on said throat, said member having spaced apertured ears at its front ends, a U-bolt surrounding said carburetor with its ends passing through the apertured ears, nuts on said bolt beyond said ears, the ends of the bolt beyond the nut being apertured, and a wire passing through said bolt apertures and having its ends connected by a seal for locking and sealing the parts in applied position. 115 120

In testimony whereof I have hereunto subscribed my name at Chicago, Cook County, Illinois.

LEONARD M. MONDRAY.
